UNITED STATES PATENT OFFICE.

GEORGE H. GILMAN, OF CLAREMONT, NEW HAMPSHIRE, ASSIGNOR TO SULLIVAN MACHINERY COMPANY, OF CLAREMONT, NEW HAMPSHIRE, A CORPORATION OF MAINE.

DIRECT-ACTING ENGINE.

1,058,668.

Specification of Letters Patent.

Patented Apr. 8, 1913.

Application filed July 6, 1911. Serial No. 637,100.

To all whom it may concern:

Be it known that I, GEORGE H. GILMAN, a citizen of the United States, and a resident of Claremont, county of Sullivan, State of New Hampshire, (whose post-office address is Claremont, New Hampshire,) have invented an Improvement in Direct-Acting Engines, of which the following description, in connection with the accompanying drawings, is a specification, like characters on the drawings representing like parts.

This invention consists of improvements in tappet actuated valves being particularly applicable to tappet valve motions employed upon direct-acting engines, such, for example, as are used with rock drilling machines.

One object of the invention is to utilize an auxiliary reversing valve in connection with a tappet actuator and in such manner that the usual objections to a tappet actuator acting directly on the main valve are overcome.

The present invention also overcomes those disadvantages which have resulted from prior attempts to actuate the main valve by pressure fluid controlled by a tappet.

Where a tappet actuator positively reciprocated in opposite directions by projections or shoulders on the piston is utilized to move directly the main controlling valve, the actuator must be relatively heavy and large and its movement relatively great to impart the required movement to the main controlling valve. The wear on such a form of actuator is considerable, resulting in a gradual change in the timing of the valve, while on the other hand it admits of little or no range of adjustment in varying the length of stroke of the piston. It has been attempted to remedy these defects by fitting the tappet itself with ports and utilizing it as a valve to reverse the main valve through the pressure fluid control of the tappet. The abnormal wear on the tappet actuator, however, tends to wear its face and cause leakage impairing the action of the valve. The chamber in which the tappet actuator works, which chamber is usually opened to a grooved part of the piston, becomes filled with pressure fluid, tending to cause leakage to opposite ends of the cylinder and preventing the employment of such chamber for lubrication purposes.

In the present invention a tappet actuator is employed positively moved alternately in opposite directions by shoulders or other projections on the piston. This serves to actuate a separate reversing valve, which latter, preferably in the form of a slide valve, actuates the main controlling valve through the control of pressure fluid. The auxiliary reversing valve may be placed in a separate chamber from the actuator and held in its seat by the pressure of the actuating fluid. It may be made very small and light and a very short stroke requiring therefore a small light tappet having but a slight movement and being subject to very little wear. This provides a condition where through the use of an auxiliary reversing valve, the length of piston stroke may be adjusted within any required limits, while the auxiliary valve is free from the disadvantages usually present in tappet actuated valves of this type.

Another object of the invention is the provision of an efficient front head for the cylinder capable of withstanding wear and preventing leakage and at the same time of ready removal or renewal.

Another object of the invention is the provision of means for equalizing the strain upon the side rods of a rock drill or other similar device.

The invention will be best understood by reference to the following description when taken in connection with the accompanying illustration of one specific embodiment thereof, submitted for illustrative purposes only, while its scope will be more particularly pointed out in the appended claims.

In the drawings: Figure 1 is a plan view of a portion of a rock drill embodying one form of the invention; Fig. 1' is a section in plan of a modified form of front head; Fig. 2 is a sectional elevation on the line 2—2 in Fig. 1 showing the valve, valve chamber and ports in their relation to the cylinder; Fig. 3 is a section on an enlarged scale showing the main valve auxiliary valve and tappet actuator; Fig. 4 is a plan view of the auxiliary valve; Fig. 5 is a sectional plan taken on the line 5—5 in Fig. 3 showing the valve plate in plan; and Fig. 6 is a cross section in elevation on the line 6—6 in Fig. 3.

Referring to the drawings and to the embodiment of the invention there illustrated,

I have shown the same embodied in a rock drill, the cylinder whereof is shown at 1, the piston at 2, and the main valve chest at 3. The compressed air or other pressure fluid which may be employed enters the valve chest 3 (from a source of supply not shown) through an appropriate supply inlet 4 and is controlled in its passage to the opposite ends of the cylinder 1 by the main controlling valve 5.

Referring to Fig. 3, the main controlling valve may be of any suitable type, but herein comprises three spools 6, 7 and 8 of equal diameter connected by portions of reduced diameter, the central spool 7 controlling communication between a supply port 9 and cylinder ports respectively 10 and 11. The port 10 is connected to the passage 12 leading to the tool end of the cylinder and the port 11 to the passage 13, leading to the head end of the cylinder. The spool 6 controls communication between the cylinder port 10 and an exhaust port 14 and the spool 8 controls communication between the cylinder port 11 and an exhaust port 15. In one position of the valve, therefore, (the position shown in Fig. 3) the admission port 9 is connected to the rear end of the cylinder through the port 11 and passage 13, the piston under such conditions being propelled forward in the direction of the arrow shown in Fig. 3. End buffers 16 and 17 are provided and on the movement of the valve to the opposite position with the spool 8 against the buffer 17 reverse conditions pertain, that is to say, pressure fluid is exhausted through the passage 12 and port 10 from the forward end of the cylinder and pressure fluid admitted through the port 11 and passage 13 to the tool or forward end of the cylinder.

To reverse the main valve 5, an auxiliary valve is employed, herein in the form of a flat slide valve 18, the latter in turn being given a short quick movement at an appropriate time by the tappet actuator 19 which is adapted to engage appropriately shaped inclined beveled shoulders 20 and 21 constituting tappet surfaces on the piston 2.

Preferably, as shown, the valve actuator is in the form of a sliding segment having an upwardly projecting tooth 22 entering the under face of the slide valve 18, the tooth and its recess in the slide valve being preferably shaped to give appropriate rolling contact between the engaging surfaces and thereby reduce the wear on the valve to a minimum.

The segment 19 slides in suitable arc-shaped guideways herein formed in the walls of the valve plate 23, the valve plate being clamped between the air chest and the cylinder and providing a seat for the slide valve 18 which therefore works in a chamber between the air chest and the valve

plate. By removing the valve chest the valve plate with the slide valve and actuator segment can be removed from the cylinder as a unit.

To control the main valve through the movement of the auxiliary valve the ends of the main valve chamber are connected respectively to passages 24 and 25 which communicate with ports 26 and 27, respectively in the top of the valve plate 23. Adjacent ports 28 and 29 in the valve plate communicate through passages 30 and 31 (see Fig. 5) with the exhaust spaces 32 and 33, respectively, the latter being in free communication with the respective ports 14 and 15 and with an exhaust outlet at the side of the cylinder and below the valve plate (not shown).

Pressure fluid is supplied directly to all parts of the auxiliary valve chamber from the admission port 9 through the passage 34 and the grooves 35 and 36 so that the slide valve is held to its seat by pressure. The valve plate has adjacent the ports 26 and 27 grooves or ports 37 and 38, respectively, and the valve has opposed co-operating grooves or ports 39 and 40.

When the valve has been moved to the position shown in Fig. 3, by the backward movement of the piston, the port 27 is opened to the actuating fluid through the ports 40 and 38 and the port 26 to the exhaust through the port 39 so that pressure fluid is admitted against the end spool 8 and exhausted from the opposite end of the main controlling valve throwing the valve to the position shown. As the piston moves forward in the direction of the arrow (Fig. 3) the shoulder 21 will engage the end of the tappet actuator and move the latter in its guideways and throw the slide valve forward, opening the port 26 to the pressure fluid supply and the port 27 to the exhaust, thereby throwing the main controlling valve to its opposite position and reversing the pressure conditions in the cylinder.

Since the tappet actuator works in a chamber separate from the auxiliary valve chamber, the space surrounding the reduced portion of the piston between the shoulders 20 and 21 may be made a dead air space and utilized as a lubricating chamber, thus not only increasing the efficiency of the engine but preventing leakage from one end of the cylinder to the other. The striking of the piston against the actuator does not tend to lift the valve from its seat or otherwise impair the action of the valve, and the slight wear which the slide valve undergoes does not in any way affect its action. When this form of valve is used on a rock drill, by adjusting the feed screw of the drill, the stroke of the piston may be adjusted from a very short stroke accompanied by a mere flutter of the valve to the full piston stroke.

If the usual feed-screw is turned so as to advance the cylinder toward the work, a point will finally be reached where the tool will be arrested by striking the stone in such a position as to bring the rear edge of the incline 21 just under the rear end of the segmental actuator 19. The latter is moved, and the valve reversed, just about the time when the tool strikes the work, and the piston 10 ton is immediately arrested by the impact, and its rearward movement begun. On this rearward movement, however, the piston has only to move a little more than the incline 21, when the forward end of the actuator encounters the incline 20, and is moved in the opposite direction. By this means, the stroke can be restricted so that the valve reverses on a very slight movement of the piston. By altering the position of the two tappet shoulders or surfaces 20 and 21 the length of piston stroke may be increased to any required length or reduced to any amount above the limit required for the movement of the valve itself. 25 The tappet and the valve can both be made very light and the tappet movement less than half of that required when the main controlling valve is actuated directly. Referring now to the construction of the 30 rock drill cylinder, the piston 2 (Figs. 1 and 2) is connected to the piston rod 41 which latter is adapted to carry at its outer end a chuck (not shown) for receiving the drill. The front end of the cylinder is 35 closed by a head of improved construction through which the piston rod passes. Referring to Figs. 1 and 2, the front head comprises a ring head 42, the upper end of which is frusto-conical and is counterbored 40 to fit accurately the outside of the cylinder. The forward end of the cylinder is preferably turned on the outside to make it concentric with the bore and to receive the overlapping end of the ring head. Seated 45 within the cone shaped end of the ring head is a split bushing 43 which latter has a projection 44 of reduced diameter entering a counterbored portion of the cylinder. The forward end of the ring head is partially split and internally threaded and is 50 provided with a gland 45 in the form of a split bushing with stud joints. The opposing ends of the gland and bushing are beveled so that they tend to compress packing 46 which is spined between them against the piston rod 41. The outside diameter of the gland is slightly greater than the piston so that the latter can be passed through the ring head. The head 55 can be packed by merely removing the gland and without unfastening the side rods of the drill. Both the bushing and the gland are bored accurately to fit the piston rod and by means of the internal projection 44 on the bushing and the external

projection on the ring head overlapping the cylinder are kept in accurate alignment. These internal and external projections on the ring head which engage the cylinder act respectively as internal and external dowels 70 centering the head with reference to the cylinder bore. They also serve to prevent leakage by providing an accurate metallic joint between the head and the cylinder. The leakage furthermore is not only prevented by the overlapping shoulder on the ring head and the bushing, but also by a slight clearance 48 which is left between the bushing and the ring head. Any pressure fluid which leaks from the forward end of 80 the cylinder tends to condense in this space and to form a water seal rendering leakage still more unlikely. The ring head as shown in Fig. 1 is provided with side wings 49 which are perforated to receive the side rods 85 50, the latter being fastened in the front head by the nuts 51 and the intervening springs 52.

In Fig. 1^a I have shown a slightly modified form of the front head, the walls of the 90 ring head being tapered for their full length and there being provided a single bushing 53 and a packing 54 placed in a groove in said bushing. This form of front head, however, is also provided with similar internal and external dowel projections to those shown in Fig. 2.

At their rear ends the side rods pass through lugs 55 on the cylinder serving to clamp the bottom head and top head 56 together. I have found that much breakage which occurs through the shock imparted to the side rods by the piston striking the bottom head can be avoided by equalizing the shock upon the two rods. For this purpose 105 I have connected the side rods by an equalizing device herein consisting of an equalizing yoke bar 57 to the ends of which the side rods are bolted. The yoke bar has a curved inner face which rests against a preferably flat seat provided in the end of the top head between the lugs 58 so that it can rock slightly thereon and tend to equalize the unequal strains to which the side rods may be subjected without in any way impairing their efficiency in clamping the cylinder and heads together. 110

While I have herein shown and described for purposes of illustration one form of the invention, it is to be understood that the 120 same is not limited to the details of construction or the form or relative arrangement of parts or to the specific application of the invention, but that extensive deviations may be made therefrom without departing from the spirit of the invention. 125

Claims:

1. The combination with a cylinder of a piston provided intermediate its ends with single tappet means, a tappet controlled 130

1. valve actuator positively moved alternately in opposite directions by the tappet means, a separate auxiliary valve moved by the actuator and a main controlling valve reversed by pressure fluid controlled by the auxiliary valve.
2. The combination with a cylinder of a piston provided with a grooved portion presenting oppositely arranged beveled shoulders to serve as tappets, a valve actuator adapted to be moved positively alternately in opposite directions by said tappets, a separate auxiliary valve moved by the actuator, and a main controlling valve reversed by the pressure fluid controlled by the auxiliary valve.
3. The combination with a cylinder of a piston provided with tappet means, a tappet controlled valve actuator adapted to be moved positively alternately in opposite directions by said tappet means comprising a sliding arc-shaped segment having a projecting tooth, a separate auxiliary valve adapted to be engaged by the tooth and moved thereby, and a main controlling valve reversed by pressure fluid controlled by the auxiliary valve.
4. In an engine, the combination with a cylinder, of a valve actuator, a piston having within said cylinder means cooperating at all times with and maintaining a positive control of said actuator to move the same alternately in opposite directions, an auxiliary valve moved by said actuator, and a main controlling valve reversed by pressure fluid controlled by said auxiliary valve.
5. In an engine, the combination with a cylinder, of a valve actuator, a piston cooperating with said actuator and maintaining throughout its stroke a positive control of said actuator to move the same alternately in opposite directions, an auxiliary valve moved by said actuator, and a main controlling valve reversed by pressure fluid controlled by said auxiliary valve.
6. The combination with a cylinder of a piston provided with tappet means, a main valve chest containing a main controlling valve, a valve plate containing guiding walls for a tappet actuator, a tappet actuator movable in said guide walls and adapted to be moved by said tappet means and an auxiliary valve working in a chamber formed by said plate and auxiliary valve between the air chest and the valve plate and actuated by said tappet actuator.
7. The combination with a cylinder, of a piston provided with a reduced tappet-carrying portion, tappet-controlled valve-actuating means, an auxiliary valve moved by said actuating means, and a main controlling valve reversed by the pressure fluid controlled by said auxiliary valve, said actuating means working in a closed chamber constituting a dead air space separated from the exhaust and pressure-supply passages of the tappet-actuated valve-chamber.
8. The combination with a cylinder, of a piston provided with a reduced tappet-carrying portion, tappet-controlled valve-actuating means, an auxiliary valve moved by said actuating means, and a main valve reversed by pressure fluid controlled by said auxiliary valve, said actuating means working in a chamber between said auxiliary valve and said piston and separated from the exhaust and pressure supply passages of the tappet-actuated valve-chamber.
9. The combination with a cylinder, of a piston provided with a reduced tappet-carrying portion, tappet-controlled valve-actuating means, pressure fluid seated valve moved by said actuating means, the space surrounding the reduced portion of the piston being separated from the exhaust and supply passages by said pressure-fluid seated valve and constituting a dead-air space.
10. In an engine, the combination with a cylinder, of a valve actuator, a piston engaging said actuator at two opposite points simultaneously and moving said actuator positively alternately in opposite directions, an auxiliary valve moved by said actuator, and a main controlling valve reversed by pressure-fluid controlled by said auxiliary valve.
11. In an engine, the combination with a cylinder, of a valve actuator, a piston having within said cylinder means for starting and completing movement of said actuator intermediate the ends of the stroke of said piston, an auxiliary valve moved by said actuator, and a main controlling valve reversed by pressure fluid controlled by said auxiliary valve.
